GUARD FOR RECEPTACLE COVERS

Filed April 13, 1949

INVENTOR,
Donald A. Freeman
BY
Otto A. Earl
ATTORNEY.

flange provided with an outwardly and upwardly turned bead on the edge of the flange comprising, a split flexible sheet metal guard band having radially disposed angularly spaced lugs struck outwardly from the lower edge thereof, the lugs having integral downwardly projecting V-shaped teeth on their longitudinal edges, the lower edge portions of the band between the lugs constituting V-shaped prongs adapted for engagement within the bead of the cover flange when the band is arranged around the flange.

3. A guard for flanged covers having upwardly facing peripheral grooves comprising, a split guard band having radially disposed angularly spaced lugs struck outwardly from the lower edge thereof, the lugs having downwardly directed teeth, the lower edge portions of the band between the lugs constituting prongs adapted for engagement within the groove of the cover flange when the band is arranged around the flange.

4. A guard for flanged covers comprising, a split flexible guard band having angularly spaced lugs

5

struck radially outward therefrom, the lugs having integral downwardly projecting teeth also struck from the band and bent downwardly from the sides of the lugs, the inner edges of said teeth tapering away from said band to space the points of the teeth radially outwardly from the band, and means for applying clamping stress between the ends of the band.
